UNITED STATES PATENT OFFICE

DAVID L. FISH, OF NEW HAVEN, CONNECTICUT

LIGHTING ATTACHMENT FOR SEWING MACHINES AND THE LIKE

Application filed August 1, 1928. Serial No. 296,714.

The present invention relates to lighting attachment devices more particularly designed for use with sewing machines, especially factory machines which are usually located so that the general lighting system of the establishment cannot be well utilized for close work, therefore, each individual sewing machine is provided with a light. According to the present invention, the improved lighting device is designed so that it may be readily applied to machines of standard make without requiring any alterations whatsoever. Furthermore, the improved light is so designed that it may be quickly adjusted into several positions. In one position the lighting attachment is so located that it lies horizontally along the arm of the machine and the light is then thrown directly on the work at the point of operation under the head of the sewing machine, for example. In another position the lighting device is elevated so that it may be shifted into a number of different radial positions. In all positions of the attachment device, the location of the same is such that the lamp and shade carried thereby cannot come in contact with any part of the machine. Besides the above feature of adjustability, the attachment device is so supported that the vibrations of the machine are not transmitted to the lamp carried by the attachment device and to attain the desired result, a cushioned or shock-absorbing device is incorporated in the construction of this attachment.

The invention will be hereinafter more fully described in detail with reference to the accompanying drawings, wherein—

Figure 1 is a perspective view showing the lighting attachment secured in one lowered position so as to lie alongside the arm of a sewing machine;

Figure 2 is a perspective showing the lighting attachment device in its elevated position;

Figure 3 is a detail plan view of part of the attachment device;

Figure 4 is a perspective view showing the cushioning or shock-absorbing device;

Figure 5 is a sectional view taken on line 5-5 of Figure 4, and

Figure 6 is a fragmentary view showing a part of the attachment device.

In accordance with the embodiment of the invention as illustrated in the accompanying drawings, the improved attachment device consists of a bracket member 1 composed preferably of a rod which is bent so as to form a substantially horizontal portion 2 at one end and an extended vertical portion 3 at the other end. An angularly disposed intermediate portion 4 and vertical portion 5 connect the two end portions together, said horizontal portion 2 carrying a flat plate 6 and said vertical portion 3 having a key 7 secured thereto and lying alongside thereof said flat plate 6 may form an integral part of the rod or as shown, the restricted neck 8 thereof is secured by a rivet in the bored end of the horizontal member 2. The bracket member 1 is adapted to be attached to the arm of a sewing machine so as to lie, when in its lower position, horizontally along the side of the said arm. In sewing machines of standardized construction, a spindle 9 for holding a spool of thread is provided and in installing the improved bracket, the plate 6 is mounted on said spindle through a perforation therein. Said plate 6 is comparatively thin so as not to interfere with the placing of the spool of thread on said spindle and said plate 6 is tapered toward one side so as to conform with the contour of the sewing machine and thus rest closely and firmly against the said arm. Sewing machines also usually have a plate 10 which covers an opening in the rear side of the arm and this plate is secured by a screw 11. This means is used to further support the bracket 1 through the medium of a plate 12 having the shouldered slotted end 13. This plate 12 is adjustably mounted on the portion 2 and is adapted to be secured to the arm by means of the screw 11. By this means of connection, the bracket 1 is rigidly secured to the arm of a sewing machine and with the adjustable means, said bracket can be determinately located.

The lighting attachment includes the usual electric lamp 14, reflector shade 15, socket 16 and tubular extension member 17. At the free end of said extension member there

is located a threaded sleeve and an insulating bushing 18 through which the electric wires 19 are passed. A sliding block 20 is mounted on the vertical extension 3 of the bracket 1 and said block 20 has a key-hole therein to fit the rod 3 and the key 7 thereon in a manner so as to prevent any turning of said block on its support when in its lowered position and in which position it is held by the thumb screw 21. The tubular extension member 17 passes through said block in a manner so that it can slide therein to permit of adjustment and to hold said extension 17 carrying the lamp and shade, in its adjusted position, the thumb screw 22 engages the groove 23 in said tubular extension so as to prevent turning thereof within the block.

It is a known fact that considerable vibration exists when a sewing machine is in operation and to eliminate the bad effects of this vibration upon the lamp carried by the lighting attachment hereinbefore described, the block 20 forming a part thereof is constructed to operate as a shock-absorber. To accomplish this purpose, the said block is built up of a number of parts including two sections 24 and 25. The extension 17 passes horizontally through the section 24 and the portion 3 of the bracket 1 passes vertically through the other section 25. The two sections 24 and 25 are separated from one another by cushioning means so that vibration cannot be transmitted from the bracket 1 to the extension 17 and the lamp and other parts carried thereby. To get the cushioning effect, the sections 24 and 25 are spaced apart and are held together by plates 26 and 27 which are secured by rivets 28. These rivets have shoulders 29 to space the plates 26-27 properly apart. An outer sleeve 30, preferably composed of rubber tubing, surrounds the rivet 28. Padding 31 consisting preferably of sheet rubber is interposed between the said plates 26-27 and through this means any vibration between the point of support of the bracket and the lamp can only be transmitted through this cushioning or shock-absorbing device. Further to prevent transmission of shock, springs or spring washers 32 and 33 are employed to provide a cushioning effect between the movable parts of the entire lighting fixture.

In Figure 1 the improved attachment device is shown in one of its lowered positions and is lying horizontally and substantially parallel with the arm of the sewing machine with the lamp thereon in close proximity with the work. In this position, it will be noted that the lighting attachment is held rigidly so that the lighting elements are not in contact with the sewing machine. The lamp can be pushed backward or brought forward the extent allowed according to the length of the extension 17. The lamp may further be moved into higher or lower posi-

tions by means of the block 20 sliding on the vertical portion 3 but in this position the key 7 prevents any turning of the block on its support. When it is desired to move the lamp into different radial positions, the fixture is raised so that the block is clear of the key 7 and in which position the block may be adjusted into the desired radial position resting on the end of said key and held in the adjusted position by the thumb screw 21.

Various modifications may be made in carrying out the details of the invention hereinbefore described but it is to be understood that any modification coming fairly within the terms of the appended claims shall be covered thereby.

I claim—

1. A device of the class described having a supporting bracket mounted on a base, means comprising a block free to slide vertically on said bracket for adjustably mounting a lamp on said bracket, said means being arranged to self-retentively retain said lamp in a predetermined fixed horizontal and parallel position relatively to said base when in its lowered or intermediate positions and when in its highest position only, said lamp being freely movable into radial positions relatively to said base. 95

2. A lighting attachment device for sewing machines comprising a bracket mounted directly on the arm of the machine, a vertically sliding block mounted on said bracket, an extension member slidably mounted in said block carrying a lamp, means for retaining said block in pre-determined fixed vertical positions on said bracket and means whereby said lamp is retained in a determined horizontal and parallel position or positions relatively to said arm. 105

3. A lighting attachment for sewing machines comprising a bracket directly secured to the arm of the sewing machine by members arranged to be secured to parts of said machine, a sliding block mounted on said bracket carrying a lamp, means for retaining said lamp in a predetermined position relatively to said arm and said block being held against rotation on said bracket by means of a key which is out of engagement with said block when the lamp is in its highest position above the sewing machine and in which position radial movement is allowed to said lamp and its support. 115

4. A device of the class described comprising a supporting bracket mounted on a base, means for adjustably and directly mounting a lamp on said bracket, said means self-retentively retaining said lamp in different vertical positions constantly parallel relatively to said base, said means comprising a block sliding on a vertical rod portion of said bracket and held against rotation thereon except when in its highest position in 120 130

which said block turns freely on said rod portion and said block being constructed and arranged to operate as a shock-absorber between the bracket and said lamp.

5 5. A lighting attachment for sewing machines comprising a bracket directly mounted on the arm of the machine and having a vertical portion; a block free to slide mounted on said vertical portion; a sliding member mounted within said block, said member carrying a lamp and a reflector therefor; said block member being adapted to slide freely on said vertical portion and having its upper and lower sides composed of resilient plates 10 extending outwardly beyond said block member, retaining plates forming part of said block; means for securing said plates together; means for supporting a light yieldingly and with limited movement supported 15 and centrally located between said retaining plates and said resilient plates whereby said block will operate as a shock absorber between said bracket and the lamp indirectly carried thereby.

20 6. In a lighting attachment as described, a bracket having a vertical rod portion at one end located in the rear of the sewing machine and a horizontal portion at the other end, said vertical portion terminating at a point above the horizontal plane of the arm of the sewing machine, intermediate horizontal and angularly disposed connecting portions, a projection alongside of said vertical portion having its upper termination at a point below the upper termination of said vertical 25 portion and above the horizontal plane of the arm of the sewing machine thereby leaving the highest portion of said vertical portion free of said projection; a block having a key-hole aperture adapted to engage said projection and to slide freely on said vertical portion and to be guided by said projection parallel to the arm of the sewing machine; said horizontal portion having a plate or enlarged end thereof adapted to fit on the spool 30 spindle on the arm of the sewing machine; an additional connecting plate adjustably mounted on said bracket adapted to be secured to the arm of the sewing machine; a tubular member carrying a lamp slidably mounted on said block and arranged to support the lamp in a horizontal and parallel position relatively to said arm of the sewing machine; said lamp and said block when at the highest position on said vertical portion being free of engagement with said projection and being adapted to be adjusted radially above said horizontal plane of the sewing machine arm.

35 Signed at New Haven, county of New Haven, State of Connecticut, this 27th day of July, 1928.

DAVID L. FISH.
